UNITED STATES PATENT OFFICE.

JACOB D. HOOVER, OF WINCHESTER, VIRGINIA.

CAR-REPLACER.

SPECIFICATION forming part of Letters Patent No. 655,778, dated August 14, 1900.

Application filed December 30, 1899. Serial No. 742,045. (No model.)

To all whom it may concern:

Be it known that I, JACOB D. HOOVER, a citizen of the United States, residing at Winchester, in the county of Frederick and State 5 of Virginia, have invented new and useful Improvements in Car-Replacers, of which the following is a specification.

This invention relates to certain new and useful improvements in car-replacers, the object being to provide a cheap, simple, and effective device for placing cars upon railway-tracks when derailed; and my invention consists in the construction and combination of the parts, as will be hereinafter set forth, 15 and specifically pointed out in the claims.

In the accompanying drawings, Figure 1 is a plan view of a car-replacer constructed in accordance with my invention, the retracking rails being shown connected to each other 20 and held in engagement with the tracks. Fig. 2 is a side view, partly in section, the section being taken on the line 2 2 of Fig. 1. Fig. 3 is a sectional view on the line 3 3, and Fig. 4 is a perspective view of one of the retracking-rails.

In the practical use of my invention I use two retracking or guide rails A A, which rails taper longitudinally, so as to be reduced to a point at one end, and the length and inclination of the rails are such that the thicker ends will be of a height which exceeds the height of the rails of the track. The retracking-rails are of such shape that the base and tread flanges converge, so that the web tapers, and said web *a* and base-flange *a'* are cut away at the thicker end to provide a wedge-shaped or angular portion *b*, which is intersected adjacent to the tread-flange *a'* by a recess *b'*. This construction leaves a part 35 of the tread-flange intact, which part *A'* is adapted to overlie the tread of the track-rails, the tread-flange of said rails entering the recesses *b'*, while the flanges of the track-rails abut against the tapered or inclined portions 40 of the retracking or guide rails A.

The projecting portions *A'* of the retracking-rails have apertures *a''*, which are countersunk on their upper sides, and through these apertures may be passed bolts or equivalent securing means for connecting thereto a bar B, said bar having attached to its under face blocks or projections *b''*, which are adapt-

ed to engage with the tread-flange of the track-rail and hold the retracking-rails against displacement. The retracking-rails are further connected to each other by cross-bars C C, which cross-bars have their outer ends bent downwardly and then outwardly to span the track-rails and maintain the retracking-rails parallel one with the other. In order to connect the bars to the retracking-rails, the webs of the rails A have lateral openings *c c*, the sides of the end portions of said openings being beveled to permit the rails A to turn upon the connecting bolts or pins which pass 60 through the tread-flanges, said beveled portions also serving as guides, which materially assist in placing the bars C in proper engagement with the rails A.

When the wheels of a car have been placed 70 upon the retracking or guide rails and moved toward the railroad-track, the flanges of said wheels will ride over the cross-bars and be guided by the tread-flanges of the retracking-rails upon the rails of the way.

The device hereinbefore described can be cheaply manufactured and is extremely simple in construction and use.

Having thus described my invention, what I claim as new, and desire to secure by Letters 80 Patent, is—

1. In a car-replacer, the combination with a pair of retracking-rails each having a tread portion which extends beyond the webs thereof, said extended tread portion having bolt-receiving apertures, transverse openings through the webs below the tread-flanges and apertures intersecting said openings, of connecting-bars and means for attaching the connecting-bars to the retracking-rails, substantially as shown.

2. In a car-replacer, a longitudinally-inclined retracking-rail having a web which is cut away on each side so as to provide a point beyond which the tread-flange projects, said 95 pointed portion of the web having therein a recess, substantially as shown, whereby the projecting end of the tread-flange of the retracking-rail will overlie the tread-flange of the track-rail.

3. In a car-replacer, a longitudinally-inclined retracking-rail which presents in cross-section horizontal base and tread flanges which are connected by a vertical web the

- higher end of the base-flange and web being tapered, said tapered portion adjacent to the tread-flange being cut away to provide a recess, the projecting portion of the tread-flange having therethrough a vertical aperture; together with a bar which is connected to said projecting portion and is provided adjacent thereto with a depending lug or block for the purpose set forth.
- 10 4. In a car-replacer, the combination with a pair of similarly-constructed retracking rails each having tread portions which extend beyond the webs of said rails, apertures through the webs of the rails, said apertures

having beveled end walls, of connecting-bars 15 the connecting-bar which is attached to the projecting ends having depending lugs or blocks the other bars having centrally-raised portions, and means for connecting the bars to the rails.

20 In testimony whereof I have hereunto set my hand in presence of two subscribing witnesses.

JACOB D. HOOVER.
